UNITED STATES PATENT OFFICE.

ELLEN STURTON, OF MAPPERLEY, NOTTINGHAM, ENGLAND.

BUTTON, STUD, OR THE LIKE.

Application filed November 22, 1927, Serial No. 235,006, and in Great Britain November 22, 1926.

This invention comprises a new or improved button, stud or the like and has particular reference to buttons or the like of the type formed in two separate parts 5 adapted to be detachably connected together, such buttons being particularly for use in fastening articles of clothing such as shirts and like garments.

The object of the present invention is to 10 provide a button of this type of particularly neat and simple construction and which when in use on a garment has the appearance of an ordinary button of the sewn-on type.

It is well known that ordinary buttons 15 are frequently damaged during laundering operations and "pearl" and bone buttons in particular are often broken and rendered useless thereby. This disadvantage in connection with ordinary sewn-on buttons is entirely eliminated in a button provided in 20 accordance with this invention since same during the time a garment is being laundered, may be readily removed from the garment and replaced thereon when it is to be again worn.

Further the same set of buttons may, if desired, be used on a number of different garments.

According to the present invention, a button, stud or the like is provided composed of 30 two separable parts, a reduced shank portion projecting from one part, a press-stud fastener functioning to connect said two parts, one fastener element permanently associated with said shank portion on one 35 part of the button, a second fastener element permanently associated with the other button part and said two button parts when connected being spaced apart by said shank 40 portion.

If desired, means hereinafter fully described in addition to the press stud, may be provided for preventing the two parts of the button from being accidentally separated.

For the purpose of more fully describing this invention, reference will now be made to the accompanying drawings wherein:—

Fig. 1, is a front elevation of that part of 50 the button which carries the female component of the press stud fastener,

Fig. 2, is a rear elevation thereof,

Fig. 3, is a rear elevation of the other 55 part of the button carrying the male component of the fastener, and

Fig. 4, is a side elevation of both the parts

of the button, that carrying the female component of the fastener being shown in cross-section.

In a convenient method of carrying this 60 invention into effect a two-part button is provided one part 1, of which is of disc shape and may conveniently be formed from imitation pearl or other material common to buttons. This disc-shaped part 1, 65 has secured to it and preferably embedded in it the female component 2, of a press-stud fastener, a convenient method of embedding same in the button being to provide a circular undercut recess 3, in the button, insert the fastener in the recess and apply pressure to cause the edge of the fastener to expand and be pressed under the 70 edge of the recess, as shown in Fig. 4.

The fastener may be of any suitable 75 known type, that illustrated having a spring wire loop 4, adapted to grip the male component of the fastener when same is pressed therein, and, if desired, holes 5, may be provided in this part 1, of the button through 80 which cotton may be threaded to give same the appearance when worn on a garment of an ordinary sewn-on button.

The other part 6, of the button, which may 85 conveniently be formed from bone, carries the male component 7, of the fastener, same being preferably embedded into the face of a boss or shank 8, of reduced diameter projecting from the main portion 6^a, of this part of the button said portion 6^a being conveniently of the same shape and size as the 90 part 1.

The male component 7, of the fastener may conveniently be embedded in the face 95 of the boss 8, in a similar manner to that in which the female component 2, is secured to the part 1.

When in use, the shank 8, and the component 7, of the fastener are passed through button holes or the like provided in the shirt or other garment, from the inside until the component 7, appears at the exterior of the garment which is then secured by snapping the female component of the fastener carried by the part 1, on the said projecting 105 part 7.

To all outward appearances the button when on the garment is identical with an ordinary sewn-on button, the thread passing through the holes 5 in the outer part 1, 110 contributing considerably to this end.

In order to prevent the two parts of the

button from becoming accidentally separated while being worn projections 9, having enlarged extremities 10, may be provided on the boss 8, of the part 6, or other 5 suitable part of the button.

The enlarged heads 10, are adapted, when the press stud is fastened, to be accommodated in a circular undercut groove 11, conveniently provided in the female component 10 of the press-stud or if desired in the button part carrying same. Enlarged openings 12, in the groove 11, allow the heads 10, of the projections 9, to be introduced into the grooves 11, after which, upon the part 2, 15 being rotated, the enlarged head of the projections engage the undercut edges of the groove and hold the two parts of the button together.

The location of the component parts of 20 the press stud may, if desired, be opposite to that shown that is to say that the female component may be secured to the boss 8 and the male component to the part 1, and further the projections 9, if provided need not 25 necessarily be on the same part carrying the male component 7, of the fastener.

I claim:—

1. A button composed of two parts adapted to be connected together in a readily detachable manner, one part being formed 30 with a reduced shank projecting therefrom, a press-stud fastener for connecting together the said two button parts, said fastener consisting of readily engageable

and separable stud and socket elements, one 35 of the fastener elements being embedded in the projecting shank of the one button part and the second fastener element being embedded in the other button part, the last said button part being arranged to engage with 40 the end of said shank surrounding the fastener part which the shank carries when the two parts of the button are united and such parts being held spaced apart by the shank portion. 45

2. A button comprising two separable parts, a reduced shank projecting from one part, a stud portion fixedly associated with said shank on the one button part, a socket 50 in the second button part for accommodating said stud portion, and projecting elements on one button portion adapted to have an interlocking engagement with a recess or recesses in the second button portion.

3. A button comprising two separable 55 parts, a reduced shank projecting from one part, a stud portion fixedly associated with said shank on the one button part, a socket in the second button part for accommodating said stud portion, elements projecting 60 from one part of the button, said elements having enlarged heads adapted to have a detachable interlocking engagement with one or more undercut recesses in the second part of the button and to be locked within said 65 recesses by rotating one part of the button relatively to the other part.

ELLEN STURTON.
